Maynard Mason of Georgetown D. C.
Letters Patent

This is to witness and record and make part of the same containing a description in the words of the said Maynard Mason himself of his improvement in the "process, by which the borings, drillings, filings, or turnings of iron are rendered available in the furnace."

To all whom it may concern. Be it known, that I, Maynard Mason of Georgetown in the County of Washington and District of Columbia, have discovered an unusual useful process, by which the borings, drillings, filings, or turnings of cast or other iron, may be fused and rendered available as pig iron in the formation of castings, or other useful purposes, and that the following is a full and exact description of my said discovery. Take the borings, drillings, filings, or turnings, and subject them to the action of a powerful press, or to repeated blows from a till hammer, drop press, ram, or to the action of any of the well known machines or instruments by which the particles may be forced together and made to adhere, so as to form lumps, partially consolidated. In doing this, every competent workman will be aware that the particles to be acted upon must be confined in a box or mould to prevent their being scattered by the pressure or blows to which they are to be subjected. The lumps, or masses of iron so formed are placed in a furnace, and heated in the same way in which pig or other iron is heated when it is to be fused or rendered available.

What I claim is, my invention or discovery, is, the bringing the particles of iron which are produced in boring, drilling, filing or turning into lumps, or masses, by subjecting them to the action of any machine or instrument calculated to effect that object and thus bringing them into a state from which they can be readily fused or rendered available as herein before set forth.

Witnessed,

R. Cruikshank
